UNITED STATES PATENT OFFICE

150,305

DESIGN FOR A COMBINED HUNTER'S BELT, SHELL POCKET, AND GAME CARRIER

Melville Keim, Chicago, Ill.

Application August 30, 1946, Serial No. 132,959

Term of patent 14 years

(Cl. D3—10)

To all whom it may concern:

Be it known that I, Melville Keim, a citizen of the United States, residing at Chicago, in the county of Cook and State of Illinois, have invented a new, original, and ornamental Design for a Combined Hunter's Belt, Shell Pocket, and Game Carrier, of which the following is a specification, reference being had to the accompanying drawing, forming a part thereof.

I claim:

The ornamental design for a combined hunter's belt, shell pocket, and game carrier, as shown.

MELVILLE KEIM.
